FIG. 23

FIG. 24

FIG. 1 is a front elevational view of a portable sewing machine showing my new design in closed position;

FIG. 2 is a head end elevational view thereof;

FIG. 3 is a rear elevational view;

FIG. 4 is a flywheel and elevational view;

FIG. 5 is a front perspective view;

FIG. 6 is a rear perspective view;

FIG. 7 is a top plan view;

FIG. 8 is a bottom plan view thereof;

FIG. 9 is a front elevational view of the portable sewing machine in an open position;

FIG. 10 is a head end elevational view thereof;

FIG. 11 is a rear elevational view;

FIG. 12 is a flywheel end elevational view;

FIG. 13 is a front perspective view, FIG. 13 is shown broken away at the top for convenience of illustration;

FIG. 14, is a rear perspective view;

FIG. 15 is a top plan view;

FIG. 16 is a bottom plan view;

FIG. 17 is a front elevational view of the portable sewing machine in another open position wherein the lower arm is exposed;

FIG. 18 is a head end elevational view thereof;

FIG. 19 is a rear elevational view;

FIG. 20 is a flywheel and elevational view;

FIG. 21 is a front perspective view;

FIG. 22 is a rear perspective view;

FIG. 23 is a top plan view; and

FIG. 24 is a bottom plan view.

I claim:

The ornamental design for a portable sewing machine, substantially as shown.
